BODYWORK

Marius Joseph Daste, Courbevoie, France

Application September 22, 1931, Serial No. 564,418
In France May 20, 1931

3 Claims. (Cl. 296—28)

A motor car bodywork having a rigid roof may be considered as consisting of four main parts or elements, which are:

- (a) The front part comprising the scuttle, the 5 front body pillars or uprights, and the frieze or top rail of the wind screen;
- (b) The upper and rear element comprising the rigid roof, the rounded back, and the back door pillars (or front door pillars if the body- 10 work has two doors);
- (c) The lower element comprising the bottom sides and the bottom, rigidly connected to the chassis;
- (d) The intermediate element comprising the 15 intermediate pillars (which do not exist in certain cases, for instance when the bodywork has two doors).

In my French Patent No. 302,657, filed Oct. 1st, 1930, and the French additional Patents Nos. 21,309 and 28,589, filed Nov. 17, 1930 and Jan. 17, 1931 respectively, I have already proposed to 20 connect these bodywork elements through elastic and flexible joints, or silent blocs, in order to obtain a silent and flexible bodywork. Now, it 25 results from my experiments that in the case of a chassis in which the transversal deformations are greater than the longitudinal deformations, the relative deformations of the elements that go to form the bodywork, as above mentioned, under 30 the effect of deformations of the chassis, can be grouped as follows: (with reference to three rectangular axes, OX in the plane of the chassis, and at right angles to the axis of the chassis, OY parallel to the axis of the chassis, and OZ 35 at right angles to the axis of the chassis): On the one hand, a slight translational displacement in a direction parallel to axis OY, and on the other hand a slight rotational displacement about axis OX or an axis parallel to OX, the last mentioned displacement being of a lower order of magnitude than the first mentioned one.

However an exception ought to be made for the connection between elements (a) and (b), that is to say between the top rail of the wind 40 screen and the front cross rail of the rigid roof, for which the relative deformations comprise, on the one hand, a slight transversal translation in a direction parallel to axis OX, and on the other hand a slight rotational displacement about axis OZ or an axis parallel to OZ.

The present invention has for its object a flexible and silent bodywork, whose characteristic feature consists in that the elastic joints which serve to connect the above mentioned elements 45 are disposed in such manner as to meet these va-

rious requirements. In particular, and contrary to what was specified in the above mentioned patents, the joints or silent blocs which connect the front pillars or uprights (which are integral with the scuttle) to the bottom sides, and also the joints or silent blocks which connect the lower part of the rounded back to said bottom sides, have their axes disposed longitudinally, that is in a direction parallel to OY.

As for the connection between the wind-screen and the front part of the roof, it has already been disclosed in the first of the above mentioned additional patents, in the embodiments shown in Figs. 8 and 9 of that additional patent.

Preferred embodiments of my invention will be hereinafter described with reference to the accompanying drawings, given merely by way of example, and in which:

Fig. 1 is a diagrammatic view showing a body-work and a chassis, and the three above mentioned axes of coordinates;

Fig. 2 is a diagrammatical view illustrating the deformations of a rigid bodywork and of a bodywork according to my invention, in the case of a longitudinal deformation of the chassis;

Fig. 3 is a perspective view of a bodywork according to my invention;

Fig. 4 is a perspective view of the various elements that go to form the bodywork that is shown as a whole in Fig. 3;

Fig. 5 is a plane view showing how the roof is assembled to the frieze or top rail of the wind-screen;

Fig. 6 is an elevational view corresponding to Fig. 5.

In Figs. 1 and 2, L₁ and L₂ are the longitudinals of the chassis whose axis is represented by line V₁, V₂. A is the front element of the bodywork; S is the upper and rear element, P is the lower element, and I is the intermediate element.

In Fig. 2, the solid lines show the bodywork according to my invention, when subjected to a deformation, and the dotted lines show a rigid bodywork subjected to a deformation.

In the case of a rigid bodywork, the bending of the chassis causes front element A₁ and rear element S₂, which both remain connected to the chassis, to become inclined. It results therefrom that the connections between upper element S₁ with A₁ and S₂ are subjected to an abnormal stress, which causes plays, breakings and noises in these connections.

According to my invention, front element A and upper and rear element S are connected to the chassis through elastic joints or slides whose

axis of translation is parallel to OY and which are capable of oscillating to a limited extent about an axis parallel to OX. It results therefrom that when the chassis is bent, elements A and S are given a translational displacement in a direction parallel to OY and are rotated about axes parallel to OX. Accordingly the connection between elements A and S is not subjected to any stress caused by the bending of the chassis.

10 Figs. 3 and 4 show how these principles are carried out.

As shown in the drawings, the bottom sides a_1 , a_2 , which are connected together through cross rails c are fixed on to the chassis d , for instance 15 by bolting.

The roof e and the rounded back part e_1 are assembled by mortice joints according to the usual practice of assembling wooden parts by means of glue; they are covered with metallic 20 sheets.

The scuttle g and the front body pillars or uprights h_1 , h_2 are assembled in the same manner.

The scuttle is supported by the dashboard panel rigidly assembled with the front cross rail 25 g_1 . For that purpose, reinforcing brackets i connect said cross rail g_1 to the front bodypillars, right h_1 and left h_2 .

The rigidity of the dashboard panel is obtained by means of strengthening stay j , bearing 30 upon the chassis between the radiator and the dashboard panel.

Lastly, the body framing includes the intermediate or rear body pillars l_1 , l_2 .

In order to effect the assembly of these different elements of the bodywork, I utilize elastic 35 joints or silentblocs fitted in the following manner:

At the front of the body, the body pillars or uprights h_1 , h_2 , which are integral with the scuttle, 40 are assembled on to the body bottom sides a_1 , a_2 through joints or silentblocs m_1 , n_1 , m_2 , n_2 , which joints are disposed in such a manner that the body pillars may have a slight sliding displacement in the horizontal direction (arrows F^2), and also 45 a slight rotational displacement about the transversal axis, (arrows f^2).

In the case of said joints m_1 , n_1 , m_2 , n_2 being silentblocs, it will be necessary to so arrange them that the pins are horizontally and longitudinally 50 disposed (in a direction parallel to OY of Fig. 1).

The rear base e_2 of the rounded back e_1 is fixed, through the lower cross piece c_2 , on to the rear cross element c of the body bottom sides a_1 , a_2 . The fixation is effected through 55 the intermediary of two elastic joints or silentblocs y_1 , z_1 , y_2 , z_2 whose axes of sliding displacement are parallel to the axis of the chassis. As in the case of the front pillars, the joints allow 60 translation displacements (arrows F^4) or rotational displacements (arrows f^4).

The body pillars o_1 , o_2 of the rounded back door are fixed either to the body bottom sides a_1 , a_2 , or directly on to the chassis, through joints or silentblocs p_1 , q_1 , p_2 , q_2 . It will be seen that the 65 joints are of the double type, i. e., comprise two parallel pins side by side, which ensures a perfect support of the pillars while permitting them slight displacements in the direction of arrows F_1 (Fig. 2) and f_1 .

70 The rounded back part e_1 and the roof e therefore follow the deformations of the chassis without the rear door pillars o_1 , o_2 (which are mounted on silentblocs p_1 , q_1 , p_2 , q_2 being affected by these deformations).

75 The intermediate pillars l_1 , l_2 , which are lo-

cated between the front and rear doors, are assembled to the body bottom sides a_1 , a_2 , or directly to the chassis, through joints or double silentblocs t_1 , u_1 , t_2 , u_2 and to roof e through silentblocs v_1 , x_1 , v_2 , x_2 . These silentblocs or joints have their axes horizontally and longitudinally disposed, in such a manner that the parts which they connect may have a slight relative translational displacement toward the front or toward the rear (arrows F^3), or a slight oscillatory displacement (arrows f^3).

This mounting of the intermediate pillars or uprights makes possible the total utilization of the play left between the doors and the uprights or pillars either for both doors or for one door 15 only.

The roof e has three points of support on the frieze or top rail r of the wind screen. The elastic joints that are utilized for the connection between said pieces have their axes parallel to 20 the axis OX of Figs. 1 and 2, in order to allow a slight relative displacement of the roof with respect to the wind-screen in a direction parallel to said axis (arrows F^0), Figs. 3, 4, and 5. This displacement is caused by the difference between 25 the transversal bendings of the chassis at the base of the front element and at the base of the upper and rear element respectively. Despite the fact that these bending displacements are infinitesimal with respect to the longitudinal bending 30 deformations, that difference corresponds to a substantial displacement of the roof with respect to the wind-screen in a direction parallel to axis OX, owing to the amplifying lever formed by the roof itself. Detailed views of these connections 35 are given by Figs. 5 and 6. With this arrangement of the silent blocs, the latter also allow a slight oscillatory movement about axis OZ (arrows f^0 , Fig. 5) of the parts that they serve to 40 connect together.

The roof, which consists at its front part of cross elements 11 and 12 connected between them by means of a wooden or a metallic plate 9 is connected to the top rail r of the wind-screen through elastic joints or silent blocs s_1 , s_2 , disposed 45 in a horizontal plane and at right angles to the axis of the chassis.

It should be noted that the arrangement of the silent blocs s_1 , s_2 allows the front part of the roof to take a slight oscillatory motion with respect to the frieze or top rail of the wind-screen about the axes of said silent blocs, that is to say about axis OX.

The embodiment which has just been described allows the construction of bodyworks entirely 55 coated with sheet iron or wood and well adapted to resist without damage and without noise to the deformations which necessarily take place in motor car chassis frames.

It should be well understood that the elastic joints that are utilized may be chosen among any of the following types, and that some joints may be of one of these types and others of another type, without departing from the principle 60 of my invention:

1. Joint comprising a closed chamber.
2. Joint comprising a prism of elastic material subjected to an initial compression.

3. Joint comprising a mass of elastic material 65 positively fixed to the movable parts.

4. Joint comprising a mass of elastic material having a substantial initial deformation in the longitudinal and radial direction (silent bloc proper).

5. Joint comprising a mass of elastic material 75

having a substantial initial deformation in the radial direction.

Likewise the elastic joint may be fixed to either of the two pieces that are connected together, 5 the assembling iron parts having optionally any shape more especially adapted to the desired mode of assembly.

While I have disclosed what I deem to be preferred embodiments of my invention, it should 10 be well understood that I do not wish to be limited thereto as there might be changes made in the arrangement, disposition and form of the parts without departing from the principle of my invention as comprehended within the scope 15 of the appended claims.

What I claim is:

1. In a motor car including a chassis, a body- 20 work comprising in combination, a rigid roof, a rounded back rigidly secured to said roof, elastic means for connecting the rear part of said rounded back to the rear part of said chassis adapted to allow said parts to slightly slide with respect to each other in a direction parallel to the longitudinal axis of the car and also to slightly rotate with respect to each other about a horizontal axis at right angles to the longitudinal axis of the car, and elastic means for connect- 25

ing the front part of said rigid roof to said chassis.

2. In a motor car including a chassis, a body-work comprising in combination, a body bottom rigidly secured to said chassis, a cross bar at the rear part of said bottom, a rigid roof, a rounded back part rigidly secured to said rigid roof, a cross member at the lower part of said rounded back, a plurality of silent blocs having their axes longitudinally and horizontally disposed for connecting said cross member to said cross bar, and elastic means for connecting the front part of said rigid roof with the front part of said body bottom. 5

3. In a motor car including a chassis, a body-work comprising in combination, a rigid roof, a rounded back rigidly secured to said roof, elastic means interposed between the rear part of said rounded back and the rear part of said chassis, said means being deformable both longitudinally 10 in a direction parallel to the axis of the motor car and angularly about a horizontal axis at right angles to said direction, with relatively smaller amplitudes for the angular deformations, and elastic means for connecting the front part 20 of said rigid roof to said chassis. 25

MARIUS JOSEPH DASTE.
